[57] CLAIM

The ornamental design for a modular carrier for tubes of paint or similar articles, substantially as shown.

DESCRIPTION

FIG. 1 is a top plan view of a modular carrier for tubes of paint or similar articles showing my new design.

FIG. 2 is a right side elevational view thereof.

FIG. 3 is a front elevational view thereof.

FIG. 4 is a rear elevational view thereof.

FIG. 5 is a left side elevational view thereof.

FIG. 6 is a bottom plan view thereof.
